UNITED STATES PATENT OFFICE.

EDWIN FRANCIS BROWN, OF CLEVELAND, OHIO, ASSIGNOR TO THE AMERICAN STEEL
AND WIRE COMPANY OF NEW JERSEY, A CORPORATION OF NEW JERSEY.

WIRE-BLOCK STRIPPER.

Application filed February 8, 1923. Serial No. 617,767.

To all whom it may concern:

Be it known that I, EDWIN FRANCIS BROWN, a citizen of the United States, and resident of Cleveland, in the county of Cuyahoga and State of Ohio, have invented

5 certain new and useful Improvements in Wire-Block Strippers, of which the following is a specification.

This invention relates to wire drawing 10 mechanism and more particularly to wire drawing blocks and bundle stripping members adapted to cooperate therewith, and has for its object the provision of a bundle stripping member adapted to be positioned 15 under the bundles of wires after the bundles have been formed.

A still further object is to provide a drawing block and stripping member having the 20 novel design, construction and combination of parts described in the following specification and illustrated in the accompanying drawings.

Heretofore, the stripping members employed for removing bundles of wire from 25 drawing blocks have been positioned on the blocks before the wire was wrapped thereon and the wire when wrapped on the body portion of the block also was engaged on the stripper. This old construction of stripping member and block, therefore, necessitated the re-positioning of a stripper member on the block after each bundle of wire was removed before a new bundle could be 30 started, and required the use of two strippers for each block unless the block remained idle, until the stripping member previously 35 removed from the block had discharged the bundle carried thereby and had been returned for use.

With the present invention the stripping member is not positioned on the block until 40 after the bundle is formed, and, therefore, a new bundle may be started on the block immediately after the previously formed 45 bundle has been removed, thus providing for constant use of the blocks, and also one stripping member may serve a plurality of blocks.

In the drawings—

50 Figure 1 is a side elevation of a stripping member, the dotted lines showing the position of the different parts in collapsed position.

Figure 2 is a top plan of a drawing block

showing the stripping member in position 55 under a bundle of wire.

Figure 3 is a sectional elevation on the line III—III of Figure 2.

Figure 4 is a transverse section on the line 60 IV—IV of Figure 1.

Referring more particularly to the drawings, the numeral 2 designates the block as a whole which comprises a circular base portion 3 and a body or drum portion 4 on which the bundles of wire are adapted to 65 be wrapped.

The body portion 4 of the block 2 is provided with a plurality of slots 5 into which the legs 6 of the stripping member 7 are adapted to be inserted. The slots 5 are 7 flared upwardly to facilitate the entrance of the legs 6 of the stripping member 7, and their lower ends 8 extend into the upper face of the base portion 3. The rear walls 9 of the slots 5 are inclined downwardly and outwardly to form cam or wedging surfaces adapted to force the legs 6 of the stripping member 7 outwardly into the lower ends 8 of the slots 5 under the bundle A of wire. The slots 5 are substantially rectangular in cross section at their lower end and are sufficiently deep to permit the legs 6 of the member 7 to move freely under the bundle of wire.

The stripping member 7 is collapsible and is adapted to be in collapsed position when entered in the slots 5. The member 7 comprises a spider head member 10 composed of a central body portion 10^a having a vertically arranged aperture 11 therein and radiating rigid arms 12. The outer ends of the arms 12 are bifurcated, providing ears 13. The legs 6 are pivotally mounted between the ears 13 on pins 14.

A vertically arranged bolt 15 is reciprocably mounted in the aperture 11 and provided with an enlarged head portion adapted to limit its downward movement and is provided with an eye portion 17 adjacent the upper end of the head to support the upper end of the head to support the stripping member 7 in attaching the stripping member to a crane or other lifting mechanism.

A second spider head member 18 is mounted on the bolt 15 adjacent its lower end and is held in position by a nut 19. The member 18 is provided with a plurality of pairs of ears 19 between which are pivotally mounted links 20 on pins 21.

The outer ends of the links 20 are bifurcated, providing ears 22 between which the legs 6 are pivotally secured by pins 23.

The bolt 15, head 18, and links 20 serve as a toggle member and, when the bolt 15 is moved upwardly relative to the head 10, the head 18 will be moved upwardly and cause the links 20 to pull the legs 6 inwardly to collapsed position, as shown in dotted lines in Figure 1.

The legs 6 are bent outwardly at their lower ends to provide supporting portions 6^a adapted to underlie the bundles of wire A.

15 A latch member 25 is pivotally mounted on ears 27 projecting upwardly from the head 10, and is adapted to be engaged over lugs 26 on the bolt 15 to lock the bolt 15 and head 10 against relative movement when it is desired to strip the wire from the block.

20 In operation, the stripping member is first collapsed by releasing the latch 25 from the bolt 15 while the stripping member is suspended from a crane or other lifting element. The head 10 will then move downwardly along the bolt 15 by gravity, while the links 20 will pull in the legs 6 to collapsed position.

While the stripping member is in collapsed position, it is lowered onto the block 2, the legs 6 being positioned in the slots 5, and by continuing the lowering movement the legs 6 are forced to ride along the inclined rear walls of the slots 5 and are thus forced outwardly into the lower end 8 of the slots 5 so that their ends 6^a underlie the bundle of wire A. With the legs in this extended position, the latch 25 is locked over the lugs 26 and the stripping member is then raised to lift the bundle of wire from the block.

I claim—

1. The combination with a wire drawing block adapted to have a bundle of wire formed thereon and having a plurality of slots therein, of a stripping member having a plurality of bundle engaging arms adapted to enter said slots and engage the bundle formed on said block, said slots being of such contour and size as to permit the entering of said arms after said bundle is formed.

2. The combination with a wire drawing block adapted to have a bundle of wire formed thereon and having a plurality of slots therein, of a collapsible stripping member having a plurality of bundle engaging arms adapted to enter said slots when in collapsed position and to be automatically moved outwardly into position under the bundle formed on said block, and means on

said stripping member for locking said bundle engaging arms in position.

3. The combination with a wire drawing block adapted to have a bundle of wire formed thereon and having a plurality of slots therein, said slots being inclined downwardly and outwardly and flaring upwardly, of a collapsible stripping member having a plurality of bundle engaging arms adapted to enter said slots when in collapsed position and to be automatically moved outwardly by the walls of said slots into position under the bundle formed on said block, and means on said stripping member for locking said bundle engaging arms in position under said bundle.

4. The combination with a wire drawing block adapted to have a bundle of wire formed thereon and comprising a base portion, a cylindrical body portion of less diameter than said base portion, said body portion and said base portion being provided with vertical slots the back walls of which are inclined downwardly and outwardly from the upper end of said body portion, of a collapsible stripping member having a plurality of bundle engaging arms adapted to enter said slots when in collapsed position, and to be automatically moved outwardly by the inclined back walls of said slots into the portion of said slots formed in said base portion of said block so as to engage under the bundle of wire formed on said block.

5. The combination with a wire drawing block adapted to have a bundle of wire formed thereon and comprising a base portion, a cylindrical body portion of less diameter than said base portion, said body portion and said base portion being provided with vertical slots the back walls of which are inclined downwardly and outwardly from the upper end of said body portion, of a collapsible stripping member having a plurality of bundle engaging arms adapted to enter said slots when in collapsed position, and to be automatically moved outwardly by the inclined back walls of said slots into the portion of said slots formed in said base portion of said block so as to engage under the bundle of wire formed on said block, and a manually operated latch for locking said arms in position under the bundle of wire on said block so that said stripping member may be lifted to strip the bundle of wire from said block.

In testimony whereof, I have hereunto signed my name.

EDWIN FRANCIS BROWN.
